US0D1094435S

(12) **United States Design Patent** (10) **Patent No.:** **US D1,094,435 S**
(45) **Date of Patent:** **** Sep. 23, 2025**

(54) **DISPLAY SCREEN OR PORTION THEREOF WITH ICON**

(71) Applicant: **Apple Inc.**, Cupertino, CA (US)

(72) Inventors: **Zachary Z. Becker**, Santa Clara, CA (US); **David Andrew Brasgalla**, Bromma (SE); **Michelle Tze Hiang Chua**, Seattle, WA (US); **Etienne Guerard**, Cupertino, CA (US); **Eduardo Sanchez Santos**, San Jose, CA (US); **Jacob Ty Sawyer**, Sunnyvale, CA (US); **Christopher I. Wilson**, San Francisco, CA (US)

(73) Assignee: **Apple Inc.**, Cupertino, CA (US)

(**) Term: **15 Years**

(21) Appl. No.: **29/872,091**

(22) Filed: **Mar. 6, 2023**

CLAIM

The ornamental design for a display screen or portion thereof with icon as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with icon showing the claimed design; and,

FIG. 2 is another embodiment thereof.

The broken lines in the figures show a display screen or portion thereof, and form no part of the claimed design.

1 Claim, 1 Drawing Sheet
